UNITED STATES PATENT OFFICE.

ARTHUR L. MEYER, OF CHIHUAHUA, MEXICO, ASSIGNOR TO ELMER HASLETT, OF SAN FRANCISCO, CALIFORNIA.

TYPEWRITER.

Application filed August 4, 1926. Serial No. 127,013.

This invention relates to typewriters and more particularly to page end indicators therefor. It is particularly desirable that a typist be informed automatically of the close approach to printing position of the end of the page or sheet being typed upon, and the invention has for an object to provide improved and simple mechanism for indicating the close approach of the end of a sheet or page to printing position. A further object is to provide improved mechanism for this purpose, with which the typist will be informed automatically of the close approach toward printing position of an end of the page or sheet, with which the distance in advance at which the information is given may be varied, which may be applied to or incorporated in present designs of typewriters without material changes in their construction or design, and which will be automatic in action, and relatively simple and inexpensive.

Various other objects and advantages will be apparent from the following description of an embodiment of the invention and the novel features will be particularly pointed out hereinafter in the appended claims.

In the accompanying drawing:

Fig. 1 is a plan of a portion of the carriage of a typewriter constructed in accordance with this invention;

Fig. 2 is a sectional elevation of the same, with the section taken approximately along the line 2—2 of Fig. 1;

Fig. 3 is another sectional elevation of a portion of the same, with the section taken approximately along the line 3—3 of Fig. 1;

Fig. 4 is a plan of a portion of the same, with a sheet inserted for printing and illustrating how the signal device is held inactive until the end of the page or sheet closely approaches printing position.

Fig. 5 is a plan of a part of the signal device; and

Fig. 6 is an elevation of the same part.

In the illustrated embodiment of the invention, the usual platen 1 is provided with platen bearing extensions 2 which are received and rotatably supported in carriage frame members 3 and 4, so that the platen may rotate about its axis in order to carry a sheet 5 to be typed upon through positions where it may be printed upon by type bars 6. The sheet or paper 5 may be guided to the platen by the usual guide or plate 7 and held

closely against the platen surface by the usual feed rollers 8 and 9 and also by the rollers 10 of a bail 11 which may be shifted toward and from the platen. The platen bearing extensions, which form the platen shaft, may be provided upon its ends with the usual knobs or handles 12 by which the platen may be rotated to feed the paper or sheet by line increments through printing position, or other paper feeding means, such as the usual ratchet device, may be employed to rotate the platen by increments and line space the sheet or paper. This ratchet device however is omitted in the interest of clarity and because it forms no part of the present invention.

A gong or bell 13 may be mounted concentrically upon one of the platen bearing extensions 2, and held against movement along the same in any suitable manner such as by a pin 14. A clutch boss 15 is secured to the adjacent face of the frame member 3 concentrically of the bearing extension 2 upon which the gong is mounted. Its end face toward the gong is provided with clutch teeth 16, with the faces of the teeth inclined in both directions circularly about the extension 2.

A sleeve 17 is rotatably and slidably mounted upon the same bearing extension 2 and upon the end face toward the boss 15 is provided with clutch teeth 18 which separably interlock with the teeth 16 of boss 15. A helical compression spring 19 is provided upon the same bearing extension 2, under compression between the sleeve 17 and the gong 13, so as to yieldingly urge the sleeve into clutching engagement with the boss 15 but permitting endwise movement of the sleeve out of clutching engagement with the boss 15.

A bracket 20 is secured to and projects from the sleeve 17 and extends at its free end toward the other end of the carriage. An arm 21 is hinged at 22 to the free end of the bracket 20, and extends along in proximity to the peripheral surface of the platen 1. A lateral arm 23 extends from the arm 21 along an end face of the platen, and terminates at its free end in a T-head 24. One branch of the T-head terminates in or carries a clapper 25 which is adapted to strike the gong as the arm 21 oscillates about pivot 22. A spring 26 secured to the bracket 20 engages with the arm 21 and yieldingly urges it in a direction to strike the gong.

A trip lever 27 is hinged by pin 28 (Figs. 5 and 6) in a slot 29 of the other free end of the T-head, so as to oscillate about an axis which is transverse to the axis of pivot 5 22. A pin 30 in the head 24 and extending across the slot 29 lies in the path of a tail of the lever 27 so as to limit movement of the lever 27 about pin 28 in one direction beyond a straight line position such 10 as shown in Fig. 6. A spring 31 secured to the under edge of the head 24 bears against the tail of the lever 27 and yieldingly urges it against the limit pin 30.

An annular ring 32 is secured, such as by 15 screws 33, to the end of the platen adjacent the gong 13, and concentrically of the bearing extension 2. The inner edge of the ring is provided with ratchet teeth 34 inclined in a common direction circularly about the 20 bearing extension 2, and rearwardly with respect to line spacing movements of the platen. The free end of the trip lever 27 extends into the ring 32 and engages with the ratchet teeth 34 as shown particularly 25 in Fig. 3. When the platen is rotated in a line spacing direction, the lever 27 will be cammed or shifted by the ratchet teeth 34 inwardly of the ring from the full line position in Fig. 3, and then released, whereupon 30 the spring 26 will return it into reengagement with the teeth 34. This movement of arm 21 through lever 27 from the ring 32 will cause an actuation of the gong 13 as the clapper hits it upon the return of the 35 lever 27 into the space between the teeth 34. Thus the passage of each tooth of the ring 32 past the lever 27 will cause an actuation of the gong.

When the arm 21 is in the position shown 40 in Figs. 1 and 3, with the lever 27 between the teeth 34, its free end will extend in a direction along, but slightly spaced from, the platen surface, the spacing being such that when the arm 21 is moved against or 45 closely to the platen, it will lie approximately parallel with the platen and the lever 27 will be out of engagement with the teeth 34. The limitation of lever 27 by the pin 30 is such that the lever is rocked idly about pin 50 28 when the platen is rotated in a direction reverse to line spacing, being returned as released by each tooth by the spring 31. When the platen is moved to line space, the 55 lever 27 is in effect a ridged continuation of the head 24 and the ratchet teeth rock the arm 21 and cause a sounding of the gong, once for each tooth of the ring.

The arm 21 is normally held against the platen, with the lever 27 out of the influence 60 of the platen, by a sheet 5 being typed upon, and hence when the lower edge of the sheet or paper 5 moves past the arm 21 during line spacing rotation of the platen, the arm 21 will be released and will be shifted by 65 spring 26 into the influence of the ring 32.

Thus upon further rotation of the platen in a line spacing direction the gong will be sounded automatically to indicate that the end of the page or sheet is being closely approached.

To vary the interval in advance of the end of the page before the gong is sounded, the sleeve 17 may be rotated to carry the arm 21 arcuately about the platen through a considerable angular extent. To facilitate such 75 rotation, the sleeve may be provided with an operating handle 35, and a branch or arm 36 of this handle may extend over an arcuate scale-bearing indicator plate 37 on the carriage frame member 3, so as to indicate the 80 different angular positions of the arm 21.

When the arm 21 is positioned to give a maximum possible advance notice, as when in the position shown on the drawing, it may not be closely confined to the platen, 85 with the result that the gong may be sounded before the end of the page is reached. To prevent this, a bearing 38 may be struck up from the upper face of the paper guide plate 7, which is usually of 90 metal, and a shaft 39 is rotatably mounted in this bearing. One end of the shaft is bent into the form of a crank 40 and upon the crank arm of this crank a roller 41 is 95 rotatably mounted. A handle arm 42 is secured upon the other end of the shaft 39, adjacent one end of the platen, by which the shaft 39 may be oscillated to carry the roller into and out of engagement with the platen, the point of engagement being approximately at the maximum rearward position of the arm 21.

The paper or sheet to be typed upon is passed over the roller 41 and between it and the platen and the roller confines the paper or sheet closely to the platen and thus holds the arm 21 closely to the platen until the end of the page is about reached and operation of the gong is desired as an indication of the page end. An intermediate portion 105 of the shaft 39 may be offset slightly, as at 43, and a leaf spring 44 secured to the paper or sheet guide 7, with the free end bearing upon the offset portion 43. The offset portion 43 is so positioned angularly with respect to the crank 40, that the spring 44 will shift the shaft 39 in either direction from a position between its limits of movement, as determined by the engagement of the roller 41 with either the platen or the paper 110 guide 7.

In the operation of a typewriter equipped with such a page end indicator, the handle 115 42 is operated to remove the roller 41 from contact with the platen. The paper or sheet 5 to be typed upon is then inserted over the roller 41 and around the platen in the usual manner. The handle 42 is then operated to shift the roller 41 against the platen and confine the sheet or paper closely to the 120 130

platen. The arm 21 is pressed against or closely towards the platen by the paper or sheet so confined to the platen, and as a result the lever 27 will be held out of the influence of the ratchet teeth of ring 32 and the arm 21 in the position of Fig. 4. The paper or sheet may be fed forwardly and upwardly through printing position as usual by rotation of the platen. As the end of the sheet 5 clears the arm 21, the latter will be shifted to carry the lever 27 into the position of Fig. 3 and under the influence and control of the ring 32. Thereafter the platen is rotated by increments in line spacing, the arm 21 will 10 be rocked against the action of spring 26 to carry the clapper 25 away from the gong and then released, owing to the camming action of the teeth 34 upon the lever 27. When released the arm 21 is returned to the position 15 of Fig. 1 by the spring 26, at which time the gong will strike the clapper and indicate the approach of a page end. The number of ratchet teeth or their length may correspond 20 to the line spaces, so that the gong will be sounded once for each line spacing movement 25 of the platen. If the platen is turned backwardly for any reason, the lever 27 will rock idly against spring 31 without shifting the arm 21.

30 The extent of advance information of the approach of a page end may be varied by shifting the handle 35 angularly. During such angular movement the clutch teeth of the sleeve 17 will cam or slide over the teeth 35 of the boss 15, the spring 19 permitting end-wise movement of the sleeve for this purpose.

It will be understood that various changes in the details, which have been herein de-

scribed and illustrated in order to explain the nature of the invention, may be made 40 by those skilled in the art within the principle and scope of the invention as expressed in the appended claims.

I claim:

1. In a typewriting machine, a rotary platen having teeth arranged in a row in the direction of rotation, a signal bell, a clapper arm for said bell operated by said teeth during rotation of the platen for line spacing, said arm having a portion extending beneath 45 a sheet which is in printing position on said platen, and at a point on said platen shortly in advance of said printing position, said portion being held by said sheet out of engagement with said teeth, said arm being 50 yieldingly biased into operative relation to said teeth for operation thereby when released by passage thereby of the lower margin of said sheet, as the latter approaches 55 printing position.

2. The typewriter substantially as set forth in claim 1, said arm being adjustable angularly about the axis of rotation of said platen to vary the point in advance of printing position on the platen where the release 60 of said arm occurs.

3. The typewriter substantially as set forth in claim 1, said arm being adjustable angularly about the axis of rotation of said platen to vary the point in advance of printing position on the platen where the release 65 of said arm occurs, said bell being mounted approximately concentrically of the platen to permit adjustment of said arm.

ARTHUR L. MEYER.
